UNITED STATES PATENT OFFICE.

ANDREW CAMPBELL, OF BROOKLYN, ASSIGNOR TO JOHN McLOUGHLIN
AND EDMUND McLOUGHLIN, OF NEW YORK, N. Y.

ELECTRICALLY-ACTUATED SHEET-STOP FOR PRINTING-PRESSES.

SPECIFICATION forming part of Letters Patent No. 291,575, dated January 8, 1884.

Application filed June 13, 1883. (No model.)

To all whom it may concern:

Be it known that I, ANDREW CAMPBELL, a citizen of the United States, residing at Brooklyn, Kings county, New York, have invented 5 an Improved Electrically - Actuated Sheet-Stop for Printing-PresSES, of which the following is a specification.

The object of my invention is to provide a printing press or machine with electrically-actuated means for holding down the sheet after it has been presented to the front guides, and before it has been seized by the grippers, in order that the tremor or jar of the machine may not shift it and destroy the register. 10 To effect this purpose, I provide two hinged fingers, mounted on opposite sides of the feed-board, and, by preference, near the end of same, adjacent to the cylinder, and arrange these to be thrown down upon the sheet by 15 means of an electro-magnet or magnets at the proper time, so as to press the sheet down firmly upon the feed-board and prevent it from shifting until seized by the grippers. The electro-magnets are in a circuit, which is 20 broken and closed at the proper time by the movements of some part of the press or machine. 25

In the drawings which serve to illustrate my invention, Figure 1 is a side elevation of a 30 portion of a cylinder printing press or machine, illustrating the application of my improvements thereto. Figs. 2 and 3 illustrate, on a large scale, the construction of the stop-finger and its operating-magnets, the former 35 being a section on line 2 2 in Fig. 3, and the latter a section on line 3 3 in Fig. 2. Fig. 4 is a plan, on a smaller scale, somewhat in the nature of a diagram, illustrating the principle upon which my device operates, and the ar- 40 rangement of the electric circuit and other parts; and Fig. 5 is a diagram showing a modified arrangement of the circuit and circuit-breaking device. 45

In Fig. 1 I have shown my sheet-stop applied to a press with swinging front guides and a lifting feed-board constructed similar to the press described in a pending application of mine; but it may as well be applied to any other form of press. In this figure, A is the cylinder, B, the feed-board, and C the time-wheel, 50

which makes one revolution to three of the cylinder. The cylinder makes three revolutions to each impression. The front guides, a, and grippers b are indicated in dotted lines. c represents the bottom guides. 55

In feeding a sheet to the grippers it is placed with its front edge against the front guides, when it will be in perfect register. At the moment the grippers close the front and bottom guides draw out of the way and the sheet 60 is seized; but in the interval between the placing of the sheet against the guides and closing of the grippers the jarring motion or tremor of the press is liable to move the sheet away from the front guides and out of 65 register. To prevent this, I employ the device I will now describe with reference to Figs. 2 and 3.

In a suitable box or case, D, mounted on the feed-board at the side, (see Fig. 4,) is placed 70 an electro-magnet, E, the armature d of which is attached to one arm, e, of a bell-crank lever fulcrumed at g. The other arm, h, of this lever extends back over the magnet, and is coupled by a link, i, to a crank-wheel, j, which oscil- 75 lates on an arbor or axis, k.

To the crank-wheel j is attached an elastic finger, l, which plays in a slot in the front of the casing D. When the magnet E is excited, its armature is attracted and the finger l is 80 thrown down upon the sheet m, upon which it exerts sufficient elastic pressure to hold the sheet firmly in place until seized. When the circuit is broken, the retracting-spring n returns the parts to the position indicated by 85 full lines in Fig. 2 and releases the sheet. The dotted lines in this figure show the magnet excited and the finger thrown down upon the sheet.

I have described but one finger and its op- 90 erative mechanism; but I prefer to employ two of these—one at each side of the board—as shown in Fig. 4.

The two magnets which actuate the fingers are in an electric circuit with a battery, dyna- 95 mo-machine, or other source of electro-motive force, F, (see Fig. 4,) and means are employed for breaking and closing said circuit at the proper time to properly operate the fingers l. This breaking and closing of the circuit is ef- 100

fected by the moving parts of the press in any way desired; but I prefer to employ the means illustrated in Fig. 1, and which I will now describe.

5 On the inner face of the time-wheel C is fixed a cam, o, which at each revolution of said wheel lifts a lever, p, hung to the main frame, and causes its free end q to contact with an elastic contact-piece, r, also fixed to the main frame. The parts q and r are in the circuit formed by the wires 1, 2, 3, and 4, the latter shown in dotted lines only in Fig. 4, it being under the feed-board. The circuit is closed after the sheet has been placed in position 10 against the front guides, and is broken an instant after the grippers close down upon the sheet. This insures the retention of the sheet in place until it is fairly seized. Fig. 5 shows a slightly-different arrangement of the circuit 15 and circuit-closing device. In this construction the press itself forms a part of the circuit, the circuit being closed only while cam o is in contact with contact-piece q.

I do not wish to limit myself to any particular form of circuit-closing device, as the number of forms that may be employed is almost infinite. It is only necessary to the successful working of my invention that the circuit shall be broken and closed by some moving part of 20 the press, and that these breaks and closures shall be effected at the proper time; nor do I wish to limit myself to the precise construction of the finger-actuating mechanism shown in Fig. 2, as this also is susceptible of many 25 formal modifications. It is only necessary that the attractive power of the magnet shall be exerted to depress or throw down the finger l. The inclosing of the mechanism is only to protect it. It is obvious also that my 30 device could be operated with a normally-closed circuit. In this case the finger would be thrown down by a spring and upheld by the magnet.

I contemplate employing as a motor a dynamo-machine operated in connection with the press; but a battery might be employed. I may also employ separate circuits and separate circuit-closing devices for each finger; but it is better, or as well, to employ one 45 circuit, as shown.

It will be observed that I arrange the fingers l to lie across the sheet m, and at right angles, substantially, to its line of movement when fed. By this arrangement the fingers are 50 prevented from disturbing the sheet when brought down upon it, as they are actuated simultaneously and very quickly by the electric current. The older forms of sheet-holders are very liable to disturb the sheet and 55 alter its register.

I may employ a secondary circuit-breaker—

that is to say, I may place this in some rapidly-moving part of the machine—say the fly-wheel, for example. This, having a circumference of six feet, would travel fifty-four feet to twelve 60 feet of the cylinder-surface, so that a circuit-breaker in the time-wheel could be in contact thirty degrees, and that of the fly-wheel three hundred and fifty degrees. By this means the circuit would be closed during the interval 65 between placing the sheet and the time of closing the fingers, except at the instant before they are absolutely in contact with the sheet. At this instant the rapid motion of the fly-wheel would break the circuit, thereby 70 lifting the sheet-holding electrical finger, and allow the sheet to be drawn away without any resistance. This will secure perfect uniformity in taking the sheet.

Having thus described my invention, I 75 claim—

1. In a cylinder printing-press, the combination, with the feed-board and front guides, of a sheet-holding finger or fingers, l, and electro-magnetic means, substantially as described, for operating said finger or fingers, whereby they are caused to press upon the sheet after it is placed against the front guides and to hold it in place until it is seized by the grippers, substantially as set forth. 80

2. The combination, with the feed-board and front guides of a printing-press, of the magnet E and its armature, the lever e h, link i, crank j, spring n, and finger l, all arranged to operate substantially as set forth. 85

3. The combination, in a printing-press having a feed-board and front guides, of two electro-magnets mounted on the sides of the feed-board, an electric generator to excite said magnets, circuit-wires, and a circuit breaking and closing device, substantially as described, whereby the moving parts of the press are 90 made to break and close the circuit, stop-fingers l, and means, substantially as described, whereby the electro-magnets are caused to 95 actuate said fingers, all arranged substantially as and for the purposes set forth. 100

4. A cylinder printing-press provided with a feed-board and front guides, and with two electrically-actuated fingers, l, arranged on opposite sides of the feed-board, and in planes substantially at right angles to the line of movement of the sheet in feeding, substantially as set forth. 110

In witness whereof I have hereunto signed 115 my name in the presence of two subscribing witnesses.

ANDREW CAMPBELL.
